CLAIM

The ornamental design for an actuator for maintaining the position of a container cover, as shown and described.

DESCRIPTION

FIG. 1 is a front elevational view showing my actuator for maintaining the position of a container cover;

FIG. 2 is a right side elevational view which is a mirror image of the left side;

FIG. 3 is a rear elevational view;

FIG. 4 is a top view; and

FIG. 5 is a bottom view.
